UNITED STATES PATENT OFFICE.

FRED I. JADEN, OF HASTINGS, NEBRASKA.

OIL CAN.

Application filed November 28, 1924. Serial No. 752,634.

To all whom it may concern:

Be it known that I, FRED I. JADEN, a citizen of the United States of America, and a resident of Hastings, in the county of Adams and State of Nebraska, have invented a new and Improved Oil Can, of which the following is a description.

My invention relates to oil cans and particularly to an oil can having pumping means 10 to forcibly eject a limited quantity of oil in each pumping operation of the pumping means.

The general object of my invention is to provide an oil can of the indicated type improved in various particulars with respect to the form and arrangement of the diaphragm, of the pumping means, spout, and the pump-operating means, whereby to promote efficiency and simplicity.

20 The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a vertical section of an oil can formed in accordance with my invention;

30 Figure 2 is a plan view of the thumb lever to operate the diaphragm of the pump.

In carrying out my invention in practice, in accordance with the illustrated example, a can body 10 is provided generally of the 35 usual cylindrical form having a handle 11. The numeral 12 indicates the can top and 13 the bottom of the body.

A flexible diaphragm 14 is provided of leather or other suitable material and the 40 edge of said diaphragm is securely held against the lower edge of the body 10 by the flanged edge 15 of the bottom 13. A spout is provided formed in sections, there being an inner section 16 extending centrally in the 45 can body 10 from a point adjacent the bottom and projecting through the cap 12. The discharge section 17 of the spout is coupled to the inner section 16 by a coupling nut 18, the screwing down of which on threaded up- 50 per end of section 16 draws the top 12 and the bottom 13 tightly in position so that the said bottom 13 tightly holds the edge of the diaphragm 14. Within the nut 18 is a ball valve 19 above which is a spring 20, said ball 55 seating on the upper end of the spout section 16 and the spring 20 pressing at its lower

end against said ball and abutting at its upper end against the lower end of the spout section 17. The lower end of the inner section 16 is threaded to engage internal threads in a plug 21 extending upwardly through the can bottom 13. The threaded lower end of the spout section 16 passes through a central hole 22 in diaphragm 14 and it receives a nut 23 above said diaphragm so that the edge portion of the diaphragm about the central hole 22 is firmly clamped between said nut 23 and the upper end of the plug 21.

The diaphragm 14 has upper and lower washers 24, 25 extending about the same outward of the central clamped portion of the diaphragm and terminating at their outer edges short of the can body 10. An oil hole 26 extends through the washers 24, 25 and through the diaphragm 14 and is controlled

60 by a flap valve 27 secured by a bolt 28 and nut 29, so that the valve opens with an upward flexure of diaphragm 14 and closes with a downward flexure of said diaphragm

65 or movement toward the bottom 13. An oil inlet hole 30 is provided in a side of the plug 21 to establish communication between the chamber in the body 10 beneath the diaphragm 14 and the lower inlet end of the

70 spout section 16.

A pump rod or wire 31 is secured at its lower end to the diaphragm 14 said lower end being threaded and passing through the washers 24, 25 and said diaphragm. Nuts 32, 33 are provided on rod 31 above and below the diaphragm to bear respectively

75 against the washers 24, 25 for firmly clamping the rod to the diaphragm. The upper end of rod 31 passes through a hole 34 in top

80 12 and the projecting upper end is operated by a thumb lever 35 having a hole 36 through

85 which said rod 31 passes, the rod having a collar 37 threaded thereon below the thumb lever 35 and a cap 38 threaded to the rod at the upper end above the lever 35. Rod 31

90 extends freely through a washer 39 seated on the top 12 at a flaring flange 40 formed on said top. A spring 41 bears at its lower end

95 against the washer 39 to maintain the same at all times seated at the opening 34 closing the same, said spring at its upper end abutting against the collar or nut 37. The arrangement is such that a depression of the lever 35 will compress said spring 41 and

100 will flex the diaphragm 14 downwardly. Upon pressure being removed from the lever 35 the spring 41 will raise the rod 31 and re-

store the diaphragm by an upward flexure. The successive downward and upward movement of the diaphragm 14 results in a feed impulse of the oil being brought about since 5 the downward movement will force oil from the under side of the diaphragm through the hole 30 to the spout section 36 and past valve 19 to and through the secured section 17. In the upward movement of the diaphragm the 10 valve 27 will open and will admit oil to the chamber in the can body 10 beneath the diaphragm for the next feed impulse.

The thumb lever 35 has side arms 42 at the front end, said arms having lugs 43 directed laterally inward toward each other, said arms 42 and their lugs 43 engaging in an annular notch or groove 44 in the nut 18 so that said nut constitutes the fulcrum of the lever.

20 I would state in conclusion that while the illustrated example constitutes a practical embodiment of my invention, I do not limit myself strictly to the exact details herein illustrated, since, manifestly the same can be 25 considerably varied without departure from the spirit of the invention as defined in the appended claims.

Having thus described my invention, I claim:

30 1. In an oil can, a can body, a diaphragm disposed in said body spaced a short distance from the bottom thereof, a valve controlled opening for the flow of oil to said space from the space above the diaphragm, 35 a spout extending into the oil can to the space beneath the diaphragm and in communication with said first space, and a rod extending from the diaphragm forwardly through the can body and top and operable to flex said diaphragm toward and from the said bottom.

2. An oil can including a can body, a flexible diaphragm so held at its edge portion to the body as to form an oil space between the diaphragm and the bottom of the can body, a spout extending into the can body and in communication with said space for the discharging of oil, a rod secured to said diaphragm and extending to the exterior of the can body, a lever engaging said rod to actuate the same for flexing the diaphragm toward the bottom of the can body, and a spring acting on said rod to restore the diaphragm after a movement by the lever.

3. An oil can including a can body, a flexible diaphragm held therein, there being a space between the diaphragm and the bottom of the can body, an opening for the passage of oil to the said space from above the diaphragm, a valve adapted to close with the flexure of the diaphragm toward said bottom and to open with a movement of the

diaphragm away from said bottom, a spout in communication with said space, and means extending to the exterior of the can body and adapted to flex said diaphragm.

4. In an oil can, a can body, a flexible diaphragm spaced from the bottom of the can body, and secured at its edge portion to said body, a valve-controlled opening to permit the flow of oil to said space, a can spout extending into the can body and through said diaphragm to said space and in communication with the latter, a plug extending through the bottom of the body and engaging the inner end of said spout, means coacting with said plug to clamp the diaphragm, and a rod extending from the diaphragm to the exterior of the can body and operable to flex said diaphragm.

5. In an oil can, a can body, a flexible diaphragm held by its edge portion in said can body to form a space between the diaphragm and the can bottom, said diaphragm having a valve-controlled opening for the flow of oil to said space with a flexure of the diaphragm, a spout composed of an inner section in said body in communication with said space, and a separate outer spout section, a nut coupling the two spout sections, a valve in said nut controlling the outflow of oil from the inner spout section, and means operative from the exterior of the can to flex said diaphragm.

6. In an oil can, a can body, a spout extending into the can body, a flexible diaphragm, means to cause a discharge of oil to the spout by the flexure of said diaphragm, including a rod secured to said diaphragm and extending through the top of the can body, a lever engaging said rod and adapted to actuate the same for flexing the diaphragm, a spring to restore the rod and diaphragm after an operation by the lever, and an element rigid with the can spout on which said lever is fulcrumed.

7. In an oil can, a can body, a spout extending into the can body, a flexible diaphragm to which the spout is secured there being a space beneath the diaphragm with which space the spout communicates, means to cause a discharge of oil to the spout by the flexure of said diaphragm, including a rod secured to said diaphragm and extending through the top of the can body, a lever engaging said rod and adapted to actuate the same for flexing the diaphragm, a spring to restore the rod and diaphragm after an operation by the lever, said lever having arms at one end thereof, said arms formed with lugs directed laterally inward toward each other, and an element on the spout engaged by said arms and lugs to afford a fulcrum for the said lever.

FRED L. JADEN.
